UNITED STATES PATENT OFFICE

135,722

DESIGN FOR A FLIGHT PLOTTING INSTRUMENT

Ernest G. Vetter, Elmira, N. Y., assignor to Jar-
dur Import Company, a copartnership con-
sisting of Lillian E. Klepper and Beatrice K.
Klepper, New York, N. Y.

Application February 22, 1943, Serial No. 109,609

Term of patent 7 years

To all whom it may concern:

Be it known that I, Ernest G. Vetter, a citizen of the United States, resident of Elmira, county of Chemung, State of New York, have invented a new, original, and ornamental Design for a Flight Plotting Instrument, of which the following is a specification, reference being had to the accompanying drawing, forming part thereof.

Figure 1 is a front view of the flight plotting instrument showing my new design, and

Figure 2 is a side view thereof.

I claim:

The ornamental design for a flight plotting instrument, substantially as shown.

ERNEST G. VETTER.
